UNITED STATES PATENT OFFICE.

ROSWELL P. COOLEY, OF CHICAGO, ILLINOIS, ASSIGNOR TO VAPOR CAR HEATING COMPANY, INC., OF CHICAGO, ILLINOIS, A CORPORATION OF NEW YORK.

HEATING SYSTEM.

1,319,924.

Specification of Letters Patent. Patented Oct. 28, 1919.

Application filed May 11, 1918. Serial No. 238,905.

To all whom it may concern:

Be it known that I, ROSWELL P. COOLEY, a citizen of the United States, residing at Chicago, in the county of Cook and State 5 of Illinois, have invented certain new and useful Improvements in Heating Systems, of which the following is a specification.

My invention relates to a heating system, and more particularly to a low pressure or 10 vapor steam heating system for railway cars. The primary object of the invention is to provide a steam heating system suitable for a railway car comprising certain arrangements of the radiating elements and controlling mechanism therefor whereby the 15 amount of heat delivered to the car, or to some portion of or locality in the car may be readily varied by increasing or decreasing the amount of radiating surface under influence of the heating medium.

A further object is to provide a heating system, having this capacity, which will be especially adapted for the heating of a railway sleeping car, the controlling arrangements being such that the occupant of a section 25 may vary the amount of heat delivered to that section to suit his own taste or requirements.

A further object of the invention is to 30 provide a car heating system comprising a main or primary radiator and two secondary radiators, together with a single valve or switching device which can be manipulated so that in one position of its operating member the heating medium will be diverted 35 from the main radiator and caused to pass through the two secondary radiators in series, while in another position of the parts of the valve device the medium will be directed from the primary radiator through 40 one of the secondary radiators only, and in a third position both secondary radiators will be cut out and the medium allowed to pass uninterruptedly through the main radiator.

A further object of the invention is to 45 provide a suitable three-position valve device for use in a heating system of the character just mentioned, or in analogous situations.

The invention consists in the new and 50 proved constructions, arrangements and devices to be hereinafter described and claimed for carrying out the above stated objects, and such other incidental objects as will appear from the following description of a 55 preferred embodiment of my invention.

This embodiment is illustrated in the accompanying drawings, wherein:

Figure 1 is a fragmentary plan view of a railway car, showing diagrammatically several elements of the heating system of my 60 invention;

Fig. 2 is a fragmentary view in perspective, showing a portion of the primary radiator and a pair of associated secondary radiators;

Figs. 3, 4 and 5 show in plan section a valve device or switching mechanism, whereby the circulation of the medium through the several radiators is controlled; Fig. 3 showing the parts of this device in the position which they assume when the secondary radiators are cut out, Fig. 4 the position of the parts when both secondary radiators are in service, and Fig. 5 the position of the parts of a valve device when one radiator is 75 cut out and the other in service;

Fig. 6 is a detail section on line 6-6 of Fig. 3;

Fig. 7 is a plan view of the bottom of the valve casing, this figure and Fig. 6 illustrating particularly the arrangement for draining the secondary radiators when cut off from the primary radiator;

Fig. 8 is a view in perspective of a suitable form of control handle for operating 85 the valve device shown in the preceding figures;

Fig. 9 is a sectional plan of the valve device taken on line 9-9 of Fig. 10; and

Fig. 10 is a vertical sectional view of the 90 valve taken on line 10-10 of Fig. 9.

Like characters of reference indicate like parts in the several figures of the drawings.

The above arrangements constituting my invention are of particular utility when embodied in a car heating system employing vapor or steam at atmospheric pressure as a heating medium, and the invention is illustrated herein as embodied in a system of this type. Referring to the drawings, 25 designates a railway sleeping car provided with the usual steam train pipe 26 adapted to receive steam from the locomotive which hauls the car. In Fig. 1 I have shown, following the usual practice, a heating apparatus for 105 each side of the car; these apparatus being identical, it will be sufficient to refer to the apparatus on one side of the car only. This apparatus comprises a primary or main radiator A which extends the entire length of 110

the car, and two secondary radiators B and C for each berth section 27 of the car. The secondary radiators B and C are connected with each other and with the primary radiator A by a three-position valve or switching device 28. There will of course be one of these valves in each section, and in accordance with the preferred form of my invention, each valve will have associated therewith 10 an operating device 29 (Fig. 8) which will have three positions corresponding to the three positions of the movable member of the valve device, the operating handle 29 being located so as to be within reach of the occupant of the section or of the lower berth when the section is made up.

The arrangements for supplying steam at substantially atmospheric pressure to the primary radiator A are the well-known devices used for vapor car heating systems, and need be described only in a general way. Steam enters the radiator A from the train pipe through a supply pipe 30, 30^a, 30^b. It flows through a pipe 31 forming part of the radiator A, then through a return bend section 32, then through a section 33 which extends preferably the entire length of the car, through another return bend section 34 at the other end of the car, and then through a pipe 35 from which it is directed into such of the secondary or section radiators as may be open. The water of condensation and any excess of steam outflows from pipe 35 of radiator A through a discharge pipe 36, 36^a, to the thermostat member of a vapor regulator 37, this vapor regulator being interposed in the ordinary way between sections 30, 30^a of the supply pipe and operating to reduce train pipe pressure sufficiently 40 to maintain the steam in the radiating coils in service at approximately atmospheric pressure. A four-way valve 38 is interposed between supply pipe sections 30^a, 30^b, and the two sections 36, 36^a of the discharge pipe. 45 This valve, which is manipulated by the car porter, serves to shut off steam from the entire apparatus on one side of the car by short-circuiting pipe section 30^a with pipe section 36^a, the steam in such case flowing 50 through the thermostat chamber of the vapor regulator in amounts just sufficient to keep the latter from getting cold and freezing up.

Fig. 2 shows a portion of the main radiator A arranged against the side wall 39 of the car, and the secondary radiators B and C for one section of the car, together with the three-position valve device 28 arranged near the floor 40 of the car. This valve device 55 comprises a casing divided by interior webs 41, 42, 43, 44, 45, and 46 into six chambers which have been designated 1, 2, 3, 4, 5 and 6 to indicate the serial order in which the steam flows through the valve device 60 when the movable element or valve member

47 is in position to permit a circulation of the medium through both secondary radiators. The valve member 47 comprises a lower disk 48 which rests on the bottom 49 of the valve casing, a top disk 50 to which the valve stem 51 is rigidly secured, and two vertical webs 52, 53 which extend between the disks providing the disks with three ports designated X, Y, Z, respectively. The valve member is revoluble and the ends 70 of the webs 52, 53 preferably make a fairly close fit with the inner faces of webs 41, 42, 43, 44, 45 and 46, these faces and the outer faces of the webs being curved.

The valve casing has the upwardly projecting boss 54 internally threaded for a bonnet 55, a spring 56 being interposed between the bonnet and the upper disk 50 of the valve member. The bonnet is formed with an internally threaded recess 57 to receive the threaded end of a gland 58 which surrounds the valve stem 51, a packing 59 being arranged between the gland 58 and the bonnet 55. To the upper end of the valve stem 51 is secured a crank 60 connected by a link 61 with a crank 62 on the end of a shaft 63 which passes through a bracket 64 arranged on the wall of the car, and is provided on its upper end with a collar 65 provided with a lug 66 to which is pivoted the controlling handle 29 referred to above. Projecting upwardly and outwardly from the edge of the upper disk 50 of the valve member is an arcuate boss 67 adapted to cooperate with stops 68, 69 on 100 the interior of boss 54. These stops limit the movement of the valve member in opposite directions. For holding the valve member in the intermediate position (that shown in Fig. 5), a locking dog 70 is provided adapted to engage a recess 71 in the edge of the lug 67. The locking dog has a head 72 which slides within a boss 73 formed on the valve casing 28. A spiral spring 74 is interposed between the head of the dog 70 and a screw plug 75 in the outer end of the boss 73. 110

The lower disk 48 of the valve member is formed with a perforation 76 outside of the web 53, and another perforation 77 between web 53 and web 52. The bottom portion 49 of the valve casing is formed with a perforation 78 and with an arcuate channel 79 leading to perforation 78. These arrangements provide drainage ports for radiators B and C when one or both of these radiators are cut off from radiator A.

Operation: The operation of the apparatus will be best understood by reference to Figs. 3, 4 and 5, taken in connection with Fig. 1. With the valve in the position shown in Fig. 4, all three radiators are active. The steam flows from the left hand pipe section of radiator A into chamber 1 of the valve device, through port X to 120

chamber 2, through secondary radiator B to chamber 3, through port Z to chamber 4, through radiator C to chamber 5, and then through port Y of the valve member into chamber 6, and back to the right hand pipe section of radiator A. It will be seen that with both secondary radiators active, the flow of the circulation through these two radiators is consecutive; that is, the steam must pass first through one and then through the other. Furthermore, before the steam can continue its course along the primary radiator A, it must pass through each and all of the secondary radiators as are open to receive steam. Inasmuch as the throttling of the high pressure steam by the vapor regulator takes place only when steam reaches the thermostat chamber of the regulator, which is arranged at the end of the discharge pipe leading from the main radiator A beyond the last of the section control valves 28, it is apparent that there can be no short circuiting of any part of the radiating system. So long as there is an abundance of steam in the train pipe, all of the radiating pipes which are open for service are kept filled with steam at atmospheric pressure, or slightly above. The main radiating coil A runs substantially the entire length of the car and is arranged in proximity to the water pipes and water fixtures of the car, with the purpose of protecting these pipes and fixtures from freezing. In the arrangement described, the steam will necessarily pass the whole length of the car through radiator A before it can be drawn off into any of the secondary radiators B and C. By this arrangement, in case there is a shortage of steam, what steam is available will be used first for the general heating of the car and protection of the water pipes and fixtures before any secondary radiator can be supplied. The web between chambers 1 and 6 is preferably formed near the bottom with a small perforation 80 which allows the water of condensation to flow through radiator A even when the valve is in position to direct the steam through one or both of the secondary radiators.

With the valve member 47 turned to the position indicated in Fig. 5, radiator B will be active, but radiator C will be cut out. The flow of steam will be as follows: From radiator A through port X to chamber 2, through radiator B to chamber 3, and through port Y to chamber 6, and thence back to radiator A. When the valve member is in this position, the drainage opening 76 will register with opening 78 in the bottom of the valve casing, thereby providing a drainage port for the water of condensation in radiator C.

By turning the valve member to the position shown in Fig. 3, both secondary radiators B and C are cut out. The flow of the steam is from chamber 1 through port X to chamber 6. With the valve in this position drainage opening 76 communicates with the channel 79 in the bottom member 70 of the valve casing, while opening 77 registers with the opening 78 in the casing. This arrangement provides means for draining both of the secondary radiators.

I claim:

1. A heating system comprising a pipe through which heating medium is adapted to pass, two radiators, and a three-position valve device which in one position of its parts connects both radiators with the aforesaid pipe so that medium flows through said radiators consecutively, in another position connects one radiator only therewith, and in a third position cuts both of said radiators from said pipe. 75
2. A heating system comprising a pipe through which heating medium is adapted to pass, two radiators, and a three-position valve device which in one position of its parts connects both radiators with the aforesaid pipe, in another position connects one radiator only therewith and provides a drainage port for the other radiator, and in a third position cuts both of said radiators from said pipe and provides drainage 90 ports for both radiators. 95
3. A heating system comprising a pipe through which heating medium is adapted to pass, two radiators, and a three-position valve device which in one position of its parts connects both radiators with the aforesaid pipe so that the medium flows through the same consecutively, in another position connects only one radiator therewith and provides a drainage port for the other radiator, and in a third position cuts both radiators from said pipe and provides drainage 100 ports for both radiators. 105
4. A heating system comprising a pipe through which heating medium is adapted to pass, two radiators, and a valve device having a revoluble member which in one position connects both radiators with the aforesaid pipe so that the medium flows through the same in series, in another position connects only one of said radiators therewith, and in a third position cuts both radiators from said pipe. 110
5. A heating system comprising a pipe through which heating medium is adapted to pass, two radiators, and a valve device having a revoluble member which in one position connects both radiators with the aforesaid pipe so that the medium flows through the same in series, in another position connects one radiator only therewith and provides a drainage port for the other radiator, and in a third position cuts both radiators from said pipe and provides drainage 115 ports for both radiators. 120
6. A heating system comprising a pipe through which heating medium is adapted to pass, two radiators, and a valve device having a revoluble member which in one position connects both radiators with the aforesaid pipe so that the medium flows through the same in series, in another position connects one radiator only therewith and provides a drainage port for the other radiator, and in a third position cuts both radiators from said pipe and provides drainage 125 ports for both radiators. 130

6. A heating system comprising a pipe through which heating medium is adapted to pass, two radiators, and a three-position valve device which in one position of its parts directs the medium from said pipe through both of said radiators consecutively and back to said pipe, in another position directs the medium from the pipe through one of said radiators and then immediately back to the pipe, and in a third position permits the steam to pass directly through the pipe, cutting out both radiators.
7. A heating system comprising a pipe through which heating medium is adapted to pass, two radiators, and a three-position valve device which in one position of its parts directs the medium from said pipe through both of said radiators consecutively and back to said pipe, in another position directs the medium from the pipe through one of said radiators and then immediately back to the pipe, and in a third position permits the steam to pass directly through the pipe, cutting out both radiators, said valve device being provided with means whereby when one or both radiators are cut out a drainage port or ports are provided through which the medium in the radiator or radiators cut out may be discharged therefrom.
8. In combination with a railway car and a source of steam supply, a pipe extending through the car, means for introducing steam therein from the supply and maintaining the same at substantially atmospheric pressure, two radiators located in the car so as to heat the same portion thereof, and a valve device having a single operating member, which device in one position of its parts brings about a circulation of steam from said pipe through both of said radiators, in another position through one of said radiators only, and in a third position cuts out both radiators.
9. In combination with a railway car and a source of steam supply, a pipe extending through the car, means for introducing steam therein from the supply and maintaining the same at substantially atmospheric pressure, two radiators located in the car so as to heat the same portion thereof, and a valve device having a single operating member, which device in one position of its parts brings about a circulation of steam from said pipe through both of said radiators, one after the other, in another position through one of said radiators only, and in a third position cuts out both radiators.
10. In combination with a railway car and a source of steam supply, a pipe extending through the car, means for introducing steam therein from the supply and maintaining the same at substantially atmospheric pressure, two radiators located in the car so as to heat the same portion thereof, and a valve device having a single operating
- member, which device in one position of its parts brings about a circulation of steam from said pipe through both of said radiators, in another position through one of said radiators only, and in a third position cuts out both radiators, said valve device providing means whereby when one or both radiators are cut out a drain port or ports are furnished through which water of condensation in said radiator or radiators may be discharged therefrom.
11. In combination with a railway car and a source of steam supply, a pipe extending through the car, means for introducing steam therein from the supply and maintaining the same at substantially atmospheric pressure, two radiators located in the car so as to heat the same portion thereof, and a valve device having a single operating member, which device in one position of its parts brings about a circulation of steam from said pipe through both of said radiators, one after the other, in another position through one of said radiators only, and in a third position cuts out both radiators, said valve device providing means whereby when one or both radiators are cut out a drain port or ports are furnished through which water of condensation in said radiator or radiators may be discharged therefrom.
12. The combination with a railway car, of a source of supply of heating medium, a primary radiating coil which extends substantially the length of the car, means for introducing heating medium into the same from the source of supply, two secondary coils arranged adjacent to each other to both heat the same portion of the car, and a valve device having a single operating member adapted in one position of its parts to bring about a circulation through all three of said coils consecutively, in another position through the primary coil and one secondary coil, and in a third position through the primary coil only, cutting out both secondary coils.
13. The combination with a railway car, of a steam train pipe, a primary radiating coil which extends substantially the length of the car, means for introducing steam into the same from said train pipe and maintaining the pressure therein at substantially that of the atmosphere, two secondary coils arranged adjacent to each other to both heat the same portion of the car, and a valve device having a single operating member adapted in one position of its parts to bring about a circulation of steam through all three of said coils consecutively, in another position through the primary coil and one of the secondary coils, and in a third position through the primary coil only, cutting out both the secondary coils.
14. The combination with a railway car, of a steam train pipe, a primary radiating

coil which extends substantially the length of the car, means for introducing steam into the same from said train pipe and maintaining the pressure therein at substantially 5 that of the atmosphere, two secondary coils arranged adjacent to each other to both heat the same portion of the car, and a valve device having a single operating member adapted in one position of its parts to bring 10 about a circulation of steam through all three of said coils consecutively, in another

position through the primary coil and one of the secondary coils, and in a third position through the primary coil only, cutting out both the secondary coils, said valve device being provided with means whereby when one or both of said secondary coils are cut out, a drainage port or ports are furnished through which water of condensation, 15 from said radiator or radiators may be discharged. 20

ROSWELL P. COOLEY.
